POLISHING MACHINE

David E. Mulholland, Reading, Pa.

Application November 2, 1936, Serial No. 103,846

44 Claims. (CL 51—78)

My invention relates to machines for polishing metal surfaces, more particularly the surfaces of sheets of stainless steel and the like, for removing the open surface and other defects usually present in metal sheets to produce what is customarily called a fundamental surface condition.

One of the principal objects of the invention is to provide extremely sensitive means for accurately controlling the pressure between the polishing roll or wheel and the metal sheet.

Another object of the invention is to provide means for producing the desired pressure between the work and the polishing roll which will readily accommodate itself to variations in thickness of a metal sheet but yet will resist such sudden or abrupt movements as would produce sudden changes in pressure on the sheet, thereby avoiding any change in the character of cut being made by the polishing roll which would result in marring the finish of the surface.

Another object of the invention is to control the rate of travel of the work past the polishing roll by the pressure producing means.

A further object of the invention is to provide improved means for supplying a coolant to the metal sheet, so that the heat generated therein by the polishing roll will be rapidly dissipated and thus enable a greater amount of stock to be removed per pass than has heretofore been possible due to warping and burning of the sheet caused by the failure of the generated heat of abrasion to escape.

A primary feature of the invention consists in providing the polishing machine with a pivoted carriage upon which is mounted a rotatable work supporting roll, the carriage being movable about its pivot to cause the work supporting roll to move toward the polishing roll of the machine.

Another feature of the invention consists in providing the pivoted carriage with means for counterbalancing the work supporting roll, so that the carriage itself will be in a state of equilibrium.

Another feature of the invention consists in providing the machine with fluid pressure means for inducing pivotal movement of the carriage to move the work supporting roll toward the polishing roll, the fluid pressure means, through the work supporting roll, serving to maintain the work in yielding engagement with the polishing roll.

A further feature of the invention consists in providing an adjustable stop limiting movement

of the work supporting roll toward the polishing roll so as to prevent the rolls from contacting each other.

Still another feature of the invention consists in providing mechanism for rotating the work supporting roll at a predetermined speed, the mechanism including means preventing rotation of the supporting roll at a speed substantially in excess of the predetermined speed whereby the supporting roll will control the rate of movement of the work past the polishing roll.

A still further feature of the invention consists in providing the carriage adjacent the work supporting roll with skids for supporting the work, which are preferably vertically and angularly adjustable with respect to the carriage.

A still further feature of the invention consists in providing means for supplying a coolant under pressure to a portion of the work immediately adjacent the portion thereof in contact with the polishing roll, the means discharging the coolant onto the work toward the polishing roll at an oblique angle to the direction of travel of the work.

Other and more specific features of the invention, residing in advantageous forms, combinations and relations of parts, will hereinafter appear and be pointed out in the claims.

In the drawings:

Figure 1 is a side elevation of the polishing machine.

Figure 2 is a plan view of the machine.

Figure 3 is a vertical sectional view taken on line 3—3 of Figure 2.

Figure 4 is a vertical sectional view taken on line 4—4 of Figure 1.

Figure 5 is a vertical sectional view taken on line 5—5 of Figure 1.

Figure 6 is a plan view of the coolant supplying means.

Figure 7 is a side elevational view of one of the coolant supplying means and the mechanism for adjusting it vertically.

Figure 8 is a detail view of the combined means for rendering inoperative the fluid pressure means which rotates the carriage in one direction for moving the work supporting roll toward the polishing roll and for simultaneously rocking the carriage in the opposite direction to move the work supporting roll away from the polishing roll.

Figure 9 is an enlarged detail sectional view taken on a line corresponding to line 9—9 of Figure 1, illustrating the means for vertically

and angularly adjusting the work supporting skids.

Figure 10 is a detail side elevational view illustrating the mechanism for operating the means for actuating the movable stop which limits movement of the work supporting roll toward the polishing roll.

Figure 11 is an enlarged detail sectional view on line 11-11 of Figure 3.

10 Figure 12 is a detail sectional view taken on line 12-12 of Figure 11.

Referring more particularly to the drawings, the polishing machine comprises generally a work feeding table or section 10, a work delivery table or section 11 and a polishing unit or section 12 which is interposed between the feeding and delivery tables.

The polishing unit has a main frame 13 which is preferably formed as a unitary casting and includes side walls 14 connected by a base 15 which forms the bottom wall of a coolant collecting chamber 16. The bottom wall 15 is spaced below flanges or the like 17 projecting outwardly from the lower portions of the side walls 14 and resting upon the floor or other suitable support provided for the polishing unit. The side walls 14 are provided with upwardly projecting portions 19 affording supports for bearings 20 of the polishing roll 21. The bearings, as well as their journals, are of exceedingly sturdy construction so as to provide in conjunction with the frame 13 a very rigid support for the polishing roll preventing it from vibrating or chattering.

The polishing roll is preferably of the character illustrated and described in my Patent No. 2,106,186, and it may comprise abrasive grain of very small size, such as No. 240 or other sizes depending upon the character of finish desired, bonded in a suitable organic material and made 40 in the form of a sleeve to fit over a drum 22 mounted on an axle 23. The axle projects beyond one of its bearings 20 and is provided with a pulley 24 having a plurality of peripheral V-shaped grooves for cooperating with a drive belt 25 formed with a plurality of V-shaped portions on its inner surface, the belt being driven by an electric motor 26 or other suitable means.

Pivottally mounted on the frame 13 of the polishing unit adjacent one end thereof is a rigid carriage or the like 27 having side members 28 which may advantageously be formed of cast metal. Intermediate their ends, the side members are respectively formed with outwardly projecting hollow trunnions 29 which are mounted 55 in bearings 30 on the main frame 13 and thus afford a pivotal support for the carriage.

Mounted on the carriage so as to be positioned beneath the polishing roll 21 is the rotatable work supporting roll 31 consisting of a drum 32 having an outer rubber covering 33 and a shaft 34, each end of which is provided with a pair of spaced bearing collars 35 and 36 which are journaled in the side members 28 of the carriage. Extending longitudinally of the carriage beneath 65 the side members thereof for imparting rotation to the work supporting roll are shafts 37, each of which is provided at one end with a worm 38 and at its opposite end with a worm wheel 39. The worms 38 are disposed within housings 40 formed 70 in the side members 28 of the carriage and they cooperate with worm wheels 41 which are mounted on shaft 34 between the bearing collars 35 and 36. Worm wheels 39 on shafts 37 are disposed within housings 42 in the side members 28 and 75 they cooperate with worms 43 formed on a shaft

44 which is coincident with the pivotal axis of the carriage and is journaled within the hollow trunnions 29 thereof. One end of shaft 44 extends beyond the adjacent side wall 14 of the main frame 13 and it is provided with a pulley 45 for cooperating with a belt 46 adapted to be driven by a suitably located electric motor 47.

As the axis of shaft 44 is coincident with the pivotal axis of the carriage, it will be readily perceived that the work supporting or back-up roll 10 may be rotated in all positions of adjustment the carriage may assume and that the mechanism for rotating it offers no resistance whatever to pivotal movement of the carriage. Moreover, as the roll is rotated through the intermediary of 15 worm gears, it cannot be over-driven by the work, due to its engagement with the more rapidly rotating polishing wheel, and accordingly the supporting roll serves to control the passage of the work past the polishing roll. 20

As the tendency of the polishing roll is to advance the travel of the sheet and the work supporting roll acts as a brake controlling the work travel, it is desirable to prevent any back-lash in the driving mechanism of the supporting roll 25 because, if there is lost motion in the mechanism, the sheet, when it first enters between the rolls, will momentarily pause in its travel and its surface will be marked. To prevent this, shaft 44 is made in two sections which are adapted 30 to be rigidly connected by a coupling having flanges 44' for receiving securing bolts. The openings in one of the flanges are in the form of arcuate slots so that before the bolts are tightened to rigidly connect the flanges, the sections 35 of shaft 44 may be rotated in opposite directions until all lost motion in the train of parts is taken up.

To maintain the carriage in a condition of equilibrium, it is provided with an adjustable 40 counterweight 48. While any suitable means may be employed for adjusting the counterweight to effect perfect balance of the carriage, this may be advantageously accomplished by mounting the counterweight on a rotatable screw-threaded 45 shaft 49 which is supported at its opposite ends by brackets 50 projecting downwardly from the carriage. At one end, shaft 49 is provided with a bevel gear 51 which meshes with a similar gear 52 formed on one end of a shaft 53 which is also 50 mounted on the carriage in suitable supports. Shaft 53 extends outwardly beyond the side of the machine and its outer end is provided with a hand wheel 54 whereby the shaft may be conveniently rotated and thus effect the necessary 55 adjustment of the counterweight.

As the carriage is perfectly balanced and its pivotal movement is resisted by only an exceedingly negligible amount of friction, the work supporting roll constitutes, in effect, a floating 60 member which may be delicately controlled for producing the precise pressure required between the polishing roll and the work to obtain optimum results.

To induce pivotal movement of the carriage 65 causing the work supporting roll to move toward the polishing roll and to yieldingly maintain the work in engagement with the latter under the desired pressure, two fluid containing chambers 66 are provided. These chambers are respectively positioned below the bearings of the work supporting roll and each consists of a cup-shaped base portion 56 and a tubular guide portion 57 within which is disposed a rubber diaphragm 58 having an annular flange which is secured be- 70 75 75

tween the base and guide portions. Resting upon the diaphragms 58 are cylindrical bosses or the like 59 which are secured to and depend from the side members of the carriage adjacent the housings 49 for the worm gears 33-41 of the work supporting roll.

The chambers 55 are connected to a fluid pressure reservoir (air being the fluid preferably used) having a capacity many times that of both chambers by means of conduits 60 which branch from a common conduit 61 provided with a manually controlled valve 62. By employing fluid pressure for maintaining the work in engagement with the polishing roll, it will be appreciated that the pressure exerted by the supporting roll may be accurately controlled. Moreover, as the work supporting roll is yieldingly maintained in engagement with the work by the fluid pressure, it will readily accommodate itself to changes of thickness in the work and it will exert a constant and uniform pressure in all positions it may assume due to variations in thickness of the work, because the volume of fluid admitted to or expelled from the chambers 55 incident to movement of the work supporting roll is but a small fraction of the total fluid within the system. Furthermore, while the carriage is mounted so as to be extremely sensitive to the changes in thickness of the work, it has sufficient mass so that it will resist such sudden or abrupt movements as would produce sudden changes in the pressure exerted by the supporting roll, which would result in changing the character of cut being made by the polishing roll and thus mar the finish of the surface.

As it is desirable to set the polishing and work supporting rolls in motion before the work is fed to the machine, means is employed for preventing the rolls from coming in contact with each other. This means may comprise horizontally adjustable stop members 63 which are slidably mounted upon T-headed projections 64 extending inwardly from the side walls 14 of the frame adjacent the portion of the carriage upon which the work supporting roll is mounted. The inner ends of the members 63 are inclined upwardly and they are adapted to cooperate with ledges or shoulders 65 which project outwardly from the side members of the carriage and have inclined upper faces disposed in planes parallel with the inclined forward ends of members 63. Thus it will be seen that movement of the carriage in a direction causing the work supporting roll to move toward the polishing roll will be arrested by the shoulders 65 of the carriage engaging the stop members 63 and that, by shifting the latter horizontally, the gap between the polishing and supporting rolls may be easily controlled.

It has been found preferable to set the stop members so that the gap between the two rolls will be approximately .010 inch less than the thickness of the sheet to be polished. As the sheet enters between the rolls, the supporting roll will, therefore, move downwardly .010 inch and thus be free to act as a floating support. The stops may be adjusted by any suitable means, such, for example, by a rack and pinion mechanism which includes a shaft 66 on which are mounted two pinions 67 for cooperating with teeth 68 formed on the upper surfaces of the stops. Shaft 66 is supported by bracket 69 and 70 which may be conveniently formed integral with the main frame 13 of the machine and at one end it is provided with a gear wheel 71 cooperating with a larger gear wheel 72 mounted on a stub

shaft 73, which is also preferably journaled in the bracket 70. Shaft 73 is provided with a hand wheel 74 whereby it may be easily rotated to effect rotation of shaft 66 and it is also provided with a calibrated dial 75 for indicating, with reference to a pointer 76 also secured to brackets 70, the space between the polishing and work supporting rolls.

As it is sometimes desirable to move the work supporting roll away from the polishing roll, suitable mechanism is provided for rendering the fluid pressure means inoperative and for simultaneously pivoting the carriage in a direction for causing downward movement of the work supporting roll. This mechanism may advantageously consist of an electric "thruster" 77 having a plunger 78 movably connected to the outer end of a lever 79 which is pivotally mounted intermediate its ends on a suitably located bracket 80. The inner end of lever 79 projects beneath the outer end of the carriage and it is adapted to engage any suitable portion thereof, such as one of the brackets 50, being guided in its movement between spaced lugs 82 formed integral with the latter, so that, when the lever is rotated in a clockwise direction by downward movement of the plunger 78 of the thruster, the outer end of the carriage will swing up and thus result in moving the work supporting roll downwardly away from the polishing roll.

For cutting off the supply of fluid pressure to the chambers 55 and for also relieving whatever pressure may be in the chambers at the time the thruster is actuated to move the work supporting roll away from the polishing roll, a valve device 83 is disposed in the main conduit 61. This device has a slide valve 84 which is movably connected to the lever 79 so that, when the plunger of the thruster is operated, the slide valve will move downwardly to shut off the supply of fluid and vent the chambers 55 to the atmosphere through a port 85 formed in the body of the valve. When the thruster is in its normal inoperative position however, the slide valve is disposed in a position enabling the free flow of fluid to the chambers, provided, of course, the manually operable valve 62 is open.

For bridging the spaces between the work supporting roll and the feeding and delivery tables, a skid 86 is mounted on the carriage closely adjacent the feeding side of the roll and a similar skid 87 is mounted on the carriage closely adjacent the delivery side of the roll. Each skid comprises a plurality of arms 88 suitably mounted in spaced relation on a supporting bar 89 which is provided adjacent each end with a pair of downwardly extending spaced lugs 90 for receiving upstanding portions 91 of members 92 to which they are pivotally connected by bolts 93. The members 92 are rotatably mounted upon the upper ends of rods 94 which are screw threaded into adjacent portions of the side members 28 of the carriage. Each of the screw threaded rods 94 is provided with a hexagonal nut 95 by which it may be easily rotated, the nuts being rigidly connected to the rods by any suitable means, such as pins or the like 96. By rotating the rods 94, it will be perceived that the skids may be easily adjusted vertically and, by untightening the bolts 93, they may be adjusted angularly. Thus simple and efficient means is provided whereby the skids may be quickly adjusted so as to properly guide the work from the feeding table to the polishing roll and from the polishing roll to the delivery table.

Mounted upon the main frame of the polishing unit on opposite sides of the polishing roll are chambers 87 for supplying coolant to portions of the work immediately adjacent the portion thereof in contact with the polishing roll. Each of the coolant supplying chambers, which may be advantageously formed of cast metal, progressively decreases in height toward its discharge end, so that the latter may be disposed near the point of contact between the work and the polishing roll and thus cause the coolant to discharge directly onto portions of the work immediately adjacent the portion in contact with the polishing roll. In the rear of each chamber 87 is formed a compartment 88 having a removable back plate 89 provided with means 100 through which coolant is supplied to the compartment. Communicating with the compartment 88 and extending forwardly therefrom are a plurality of ducts 101, the discharge ends of which are disposed as indicated at 102 so as to cause the coolant to issue therefrom at an oblique angle to the direction of travel of the work. By causing the coolant to discharge onto the work in this manner under a pressure preferably in excess of 250 pounds per square inch, the coolant will flow transversely of the work at a velocity which will effect such efficient results that the polishing wheel may remove a greater amount of stock per pass than has heretofore been considered possible.

Each of the coolant supplying chambers is vertically movable within guides 103 formed on the inner sides of the side walls 14 of the main frame of the polishing unit so that, as the polishing wheel wears, they may be easily adjusted. The mechanism for effecting vertical adjustment of each of the chambers may advantageously consist of a transversely extending shaft 104 which is provided with bevel gears 105 for respectively cooperating with similar gears 106 mounted on the lower ends of vertically disposed shafts 107 which are respectively screw threaded at their upper ends for cooperating with the end portions of the chamber. The horizontal shaft 104 may be conveniently journaled in brackets 108 rigid with the side walls of the frame 14 and at one end it extends through the adjacent side wall of the frame where it is provided with a hand wheel 109. The polishing wheel is preferably enclosed by a sheet metal hood 110 within which is mounted means for freeing the periphery of the polishing roll of particles of grit and other waste material which may adhere thereto. This means serves to forcibly project a fluid medium at an exceedingly high pressure against the entire surface of the roll at least once in each revolution from a series of nozzles 111 mounted in a header 112 which is connected to suitable means, not shown, for supplying fluid under pressure. The discharge ends of the nozzles 111 are disposed closely adjacent the periphery of the polishing roll, so that the fluid issuing therefrom will, upon each revolution of the roll, readily dislodge particles of grit and other matter adhering to its surface before the adhering matter becomes impacted by repeated contacts with the work and gathers additional matter which would result in an adhering aggregate being built up on the surface of the roll.

In addition to the fluid pressure means for cleaning the surface of the polishing roll, a plurality of deflecting baffles 113 are mounted within the hood 110 which serve to deflect and conduct off to the sides of the roll the coolant and clean-

ing fluid which discharges tangentially from the roll and is laden with abrasive wastes and thereby prevent this adulterated fluid, by being deflected from the hood, from entering the stream of filtered coolant emerging from the nozzles on the entry side of the roll. Each of the deflected baffles 113 is formed with a main body portion of arcuate shape, one end of which is attached to the inside of the hood and the opposite or free end of which is provided with a strip of rubber 114 for engaging the surface of the roll.

While the work feeding table may be of any suitable construction, it is preferably provided with a plurality of rollers 115 which are driven through a train of gears 116. The axes of the rollers 115 are preferably inclined with respect to the axes of the polishing and work supporting rolls so as to maintain the work against the guide bar 117 with which the table is provided and thus insure the work being fed in the proper position to the polishing roll.

The delivery table 11 is also provided with a plurality of rollers 118 but these rollers need not be positively driven. Interposed between the forward end of the delivery table and the rear end 25 of the skid 87 are a plurality of rollers 119 for conducting the work from the skid to the delivery table. These rollers are mounted in supports 120 carried by adjustable means 121 similar to the adjusting means of the skids whereby the 30 rollers may be vertically and angularly adjusted.

The rear end of the feeding table and the front end of the delivery table are provided with means whereby they may be vertically adjusted so that they may, at all times, be disposed at substantially the same elevation as the skids 86 and 87 which are adjustable to take care of the work level as wear occurs on the grinding drum and the work supporting roll. The means for vertically adjusting the elevation of the rear end 35 of the feeding table and the front end of the delivery table may, if desired, consist of floor engaging pads or the like 122 having screw threaded portions 123 which extend upwardly into the vertical supports 124 of the tables and 40 are provided with nuts 125 engaging the lower ends of the vertical supports. The feeding table is of such height at its front end that it will be several inches above the highest point to which it is ever necessary to elevate the rear end and the 45 rear end of the delivery table is likewise several inches higher than the front end thereof so that the coolant, as it spreads upon the work, will always tend to flow toward the center of the machine where it may be collected in the chamber 18.

From the foregoing, it will be perceived that I have devised a rugged polishing machine having extremely sensitive means which may be accurately controlled to maintain the work against the polishing roll under the precise pressure desired. Furthermore, by reason of the means employed for supplying coolant to portions of the work immediately adjacent the portion thereof in contact with the polishing roll, a greater amount of stock may be removed per pass than has heretofore been possible and by removing all loose particles of grit and waste matter from the surface of the polishing roll, a polished or ground surface with substantially uniform characteristics of a predetermined degree is obtained.

The operation of applicant's device is as follows: The sheet to be polished is placed upon the driven rolls 115 and due to the angulari-

of these rolls the sheet is caused to move both longitudinally and transversely until it contacts the guide member 117, at which time the direction of movement of the sheet will be at right angles to the axes of the polishing and work supporting rolls. The rotation of the rollers 115 feed the sheet over the skid table and into the space between the abrasive or polishing roll and the work supporting roll. The polishing roll rotated at high speed in the direction of the arrows, shown on Figures 1 and 3 tends to force the sheet at a high rate of speed toward the rolls 113. This action is prevented owing to the fact that the work supporting roll is positively driven at a definite rate of speed and therefore limits the speed of passage of the plate. The supporting roll, owing to its pivotal support and to the diaphragm, is capable of fine adjustment so that the pressure of the plate against the polishing roll may be regulated so as to limit the amount of material removed from the surface of the plate. The adjustment of the skid table permits the skid table to be moved to compensate for the difference in diameter of the polishing roll due to wear of its abrasive surface. The stop mechanism illustrated in detail in Figures 10, 11 and 12 provides for an exceedingly accurate gage of the pressure which will be applied by the work supporting roll and at the same time prevents the work supporting roll from contacting with the polishing or abrasive roll between the passage of one plate and the next.

Various modifications and changes in details of construction of the specific embodiment of the invention described and illustrated herein may, of course, be made without departing from the spirit of the invention as defined by the appended claims.

What I claim is:

1. A machine for polishing metal sheets and the like, including a rotatable polishing roll, means for driving the polishing roll, a work supporting roll disposed beneath the polishing roll and movable with respect thereto in a substantially vertical direction, and mechanism for rotating the work supporting roll at a predetermined speed, said mechanism including means preventing the rotation of the supporting roll at a speed substantially in excess of said predetermined speed whereby said supporting roll controls the movement of the work past the polishing roll.

2. A machine for polishing sheets and the like, including a polishing roll, means for rotating the polishing roll, a vertically adjustable work supporting roll beneath the polishing roll, fluid pressure means for moving the work supporting roll upwardly to force the work into engagement with the polishing roll, and mechanism for rotating said work supporting roll at a speed less than the speed of the polishing roll, said mechanism including means for maintaining the speed of rotation of the supporting roll less than the speed of rotation of the polishing roll.

3. A machine for polishing metal sheets and the like, including a rotatable polishing roll having a substantially unyielding surface, means for driving the polishing roll, a work supporting roll having a yielding surface disposed beneath the polishing roll and movable with respect thereto in a substantially vertical direction, and mechanism for rotating the work supporting roll at a predetermined speed which is less than the speed of the polishing roll, said mechanism including means preventing rotation of the sup-

porting roll at a speed substantially in excess of said predetermined speed whereby said supporting roll controls the movement of the work past the polishing roll.

4. A machine for polishing metal sheets and the like, including a polishing roll, a vertically movable work supporting roll disposed beneath the polishing roll, fluid pressure means providing a yielding support for the work supporting roll and for moving it toward the polishing roll, and mechanism for rotating said supporting roll including means movable with the latter whereby said mechanism is operative to drive said supporting roll in all positions it may assume.

5. A machine for polishing metal sheets and the like, including a polishing roll, a work supporting roll, means for rotating the work supporting roll, fluid pressure means for moving the work supporting roll toward the polishing roll, and an adjustable stop for limiting the extent of movement of said work supporting roll toward the polishing roll.

6. A machine for polishing metal sheets and the like, including a polishing roll, a work supporting roll movable toward the polishing roll, fluid pressure means for yieldingly maintaining the supporting roll in contact with the work, and adjustable means limiting movement of the supporting roll toward the polishing roll whereby the supporting roll may be initially set so as to provide a predetermined gap between it and the polishing roll.

7. A machine for polishing metal sheets and the like, including a polishing roll, a pivotally mounted carriage, a rotatable work supporting roll mounted on the carriage and disposed beneath the polishing roll, the axis of the supporting roll and the pivotal axis of the carriage being laterally spaced and being disposed in substantially the same horizontal plane, and means co-operable with the carriage adjacent the supporting roll to cause said carriage to pivot and thereby move the supporting roll relatively to the polishing roll.

8. A machine for polishing sheets and the like, including a polishing roll, a pivoted carriage, a rotatable work supporting roll disposed beneath the polishing roll and mounted on said carriage, said work supporting roll being spaced horizontally from the pivotal axis of the carriage, and yieldable means co-operable with the carriage at a point spaced from the pivotal axis thereof for causing the supporting roll to maintain the work in contact with the polishing roll.

9. A machine for polishing metal sheets and the like, including a polishing roll, a pivoted carriage, a work supporting roll disposed beneath the polishing roll and mounted on said carriage, fluid pressure means for causing said carriage to move the work supporting roll toward the polishing roll, said fluid pressure means serving to maintain the work in yielding engagement with the polishing roll.

10. A machine for polishing metal sheets and the like, including a polishing roll, a pivoted carriage, a work supporting roll disposed beneath the polishing roll and mounted on said carriage on one side of the pivotal axis thereof, means inducing pivotal movement of the carriage for causing the work supporting roll to move toward the polishing roll, and means on said carriage for counterbalancing the work supporting roll.

11. A machine for polishing metal sheets and the like, including a polishing roll, a pivotally

- mounted carriage, a work supporting roll disposed beneath the polishing roll and mounted on said carriage, means on said carriage counterbalancing said work supporting roll, means for pivoting said carriage to move the work supporting roll toward the polishing roll, and adjustable means for limiting movement of said carriage in a direction causing the work supporting roll to move toward the polishing roll.
- 10 said adjustable means serving to prevent the supporting roll from contacting the polishing roll.
12. A machine for polishing metal sheets and the like, including a polishing roll, a carriage pivotally mounted intermediate its ends, a work supporting roll mounted on the carriage on one side of its pivotal axis, means on the carriage on the other side of its pivotal axis for counterbalancing the work supporting roll, and fluid pressure means for inducing pivotal movement 15 of the carriage to move the work supporting roll toward the polishing roll.
13. A machine for polishing metal sheets and the like, including a polishing roll, a carriage pivotally mounted intermediate its ends, a work supporting roll mounted on the carriage on one side of its pivotal axis and movable toward the polishing roll upon pivotal movement of the carriage in one direction, means mounted on the carriage for counterbalancing the work supporting roll, and yieldable means cooperable with the carriage for resisting movement thereof in a direction causing the supporting roll to move away from the polishing roll.
14. A machine for polishing metal sheets and the like, including a polishing roll, a carriage pivotally mounted intermediate its ends, a work supporting roll mounted on the carriage on one side of its pivotal axis, and adjustable means mounted on the carriage on the other side of its 20 pivotal axis for counterbalancing the work supporting means, and means for inducing pivotal movement of the carriage to cause the work supporting roll to move toward the polishing roll.
15. A machine for polishing metal sheets and the like, including a polishing roll, a pivoted carriage, a work supporting roll mounted on the carriage in spaced relation to the pivotal axis thereof, and mechanism for inducing pivotal movement of the carriage to move the work supporting roll toward the polishing roll, said mechanism including a flexible diaphragm, a member mounted on the carriage engageable with the diaphragm, and fluid pressure means for actuating said diaphragm.
16. A machine for polishing metal sheets and the like, including a polishing roll, a pivoted carriage, a rotatable work supporting roll mounted on the carriage in spaced relation to the pivotal axis thereof, means for inducing pivotal movement of the carriage to move the work supporting roll toward the polishing roll, and mechanism for rotating the work supporting roll including a rotatable shaft having its axis coincident with the pivotal axis of the carriage.
17. A machine for polishing metal sheets and the like including a polishing roll, a pivoted carriage, a rotatable work supporting roll mounted on the carriage in spaced relation to the pivotal axis thereof, means for inducing pivotal movement of the carriage to move the work supporting roll toward the polishing roll, and mechanism for rotating the work supporting roll including a main drive shaft having its axis coincident with the pivotal axis of the carriage and means carried by the carriage operatively connecting said drive shaft and work supporting roll for imparting rotation to the latter.
18. A machine for polishing metal sheets and the like, including a polishing roll, a pivoted carriage, a work supporting roll mounted on the carriage in spaced relation to the pivotal axis thereof, skids mounted on the carriage adjacent the supporting roll for supporting the work, means for inducing pivotal movement of the carriage for moving the supporting roll and skids 10 toward the polishing roll.
19. A machine for polishing metal sheets and the like, including a polishing roll, a pivoted carriage, a work supporting roll mounted on the carriage in spaced relation to the pivotal axis 15 thereof, skids carried by said carriage and disposed on opposite sides of the supporting roll for supporting the work, and means for inducing pivotal movement of the carriage to move the supporting roll and skids toward the polishing roll.
20. A machine for polishing metal sheets and the like, including a polishing roll, a pivoted carriage, a work supporting roll mounted on the carriage in spaced relation to the pivotal axis 25 thereof, skids mounted on the carriage adjacent the supporting roll for supporting the work, means for inducing pivotal movement of the carriage for moving the supporting roll and skids toward the polishing roll, and means for vertically 30 adjusting said skids with reference to said carriage.
21. A machine for polishing metal sheets and the like, including a polishing roll, a pivoted carriage, a work supporting roll mounted on the carriage in spaced relation to the pivotal axis thereof, skids carried by said carriage and disposed on opposite sides of the supporting roll for supporting the work, means for inducing pivotal movement of the carriage to move the supporting roll and skids toward the polishing roll, and means for vertically and angularly adjusting 35 said skids with reference to the carriage.
22. A machine for polishing metal sheets and the like, including a polishing roll, a pivoted carriage, a work supporting roll mounted on the carriage, fluid pressure means for inducing pivotal movement of the carriage to move the supporting roll toward the polishing roll, and means for pivoting the carriage to cause the supporting roll 40 to move away from the polishing roll.
23. A machine for polishing metal sheets and the like, including a polishing roll, a pivoted carriage, a work supporting roll mounted on the carriage, fluid pressure means for inducing pivotal movement of the carriage to move the supporting roll toward the polishing roll, and means for rendering said fluid pressure means inoperative and for simultaneously inducing pivotal movement of the carriage to cause the supporting roll to move 45 away from the polishing roll.
24. A machine for polishing metal sheets and the like, including a polishing roll, a work supporting roll, and a plurality of means respectively disposed on opposite sides of a vertical plane passing through the axis of the polishing roll for supplying a coolant under pressure to the portions of the work immediately adjacent the portion thereof in contact with the polishing roll, one of said coolant supplying means causing the coolant discharging therefrom to flow parallel to the axis of said roll in one direction and the other of said means causing the coolant discharging from it to flow parallel to the axis of the roll but in the opposite direction.

25. In a machine for polishing metal sheets and the like, the combination with work supporting means, a rotatable polishing roll having a substantially inflexible polishing surface containing abrasive grains, a hood for said roll, and means disposed within said hood for forcibly projecting a fluid medium against the surface of the roll substantially normal thereto for removing loose particles of abrasive grit and other waste material 10 adhering thereto.

26. In a machine for polishing metal sheets and the like, the combination with work supporting means, a rotatable polishing roll having a substantially inflexible polishing surface containing abrasive grains, means including a plurality of nozzles having their discharge ends closely adjacent the surface of the roll substantially normal thereto for forcibly projecting a fluid medium against said surface for removing loose particles of abrasive grit and other waste material adhering thereto.

27. In a machine for polishing metal sheets and the like, the combination with a work supporting roll, of a rotatable polishing roll having a polishing surface containing abrasive grains, means for forcibly projecting a fluid medium against said surface for removing loose particles of abrasive grit and other waste material adhering thereto, a hood for said roll, and means within said hood for deflecting and conducting off to one side of the roll the fluid medium discharging tangentially from the roll after being projected thereon.

28. In a polishing machine, a rotatable polishing wheel, a hood about said wheel, a plurality of rigid, arcuate-shaped baffles fixedly secured at one end to said hood and extending inwardly in the direction of the wheel periphery, said baffles having a concave side portion disposed above the axis of said wheel and towards which the operating face of the wheel rotates, and rubber flappers carried by said baffles and projecting beyond the free end thereof to continuously engage the surface of the wheel to remove therefrom during one rotation of the wheel any adhering particles of abrasion and direct them into the concavity of said baffles whose concave surface forms conducting troughs to carry away the removed waste particles of abrasion.

29. In a machine for polishing metal surfaces, a rotatable polishing wheel, a work support, means for pivoting said work support intermediate its ends, means on said work support on one side of the pivot means to engage the work for backing up the latter and to control the feed thereof, counterbalancing means on the work support on the other side of said pivot means to neutralize gravitational effect on the work-engaging means, a diaphragm, a boss attached to said work support resting on said diaphragm and out of frictional sliding contact with other parts, and a fluid pressure chamber for operating said diaphragm to urge the work through the work engaging means of said work support towards said polishing wheel.

30. In a machine for polishing metal surfaces, a rotatable polishing wheel, a work support, means for pivoting said work support intermediate its ends, means on said work support on one side of the pivot means to engage the work for backing up the latter and to control the feed thereof, counterbalancing means on the work support on the other side of said pivot means to neutralize gravitational effect on the work-engaging means, a diaphragm, a boss attached to said work support resting on said diaphragm and

out of frictional sliding contact with other parts, and controlled fluid pressure means for moving said diaphragm to urge the work through the work-engaging means toward said polishing wheel.

31. In a machine for polishing metal surfaces, a rotatable polishing wheel, a work support, means for pivoting said work support intermediate its ends, means on said work support on one side of the pivot means to engage the work for backing up the latter and to control the feed thereof, counter-balancing means on the work support on the other side of said pivot means to neutralize gravitational effect on the work-engaging means, a diaphragm, a boss attached to said work support resting on said diaphragm and out of frictional sliding contact with the other parts, and controlled pressure means for moving said diaphragm to urge the work through the work-engaging means of said work support toward said polishing wheel.

32. In a machine for polishing metal surfaces, a rotatable polishing wheel, a work support, means for pivoting said work support intermediate its ends, a rotatable member on said work support on one side of the pivot means to engage the work for backing up the latter and to control the feed thereof, counter-balancing means on the work support on the other side of said pivot means to neutralize gravitational effect on the work-engaging means, a diaphragm, a boss attached to said work support resting on said diaphragm and out of frictional sliding contact with other parts, and controlled pressure means for moving said diaphragm to urge the work through the work-engaging means of said work support toward said polishing wheel.

33. In a machine for polishing metal surfaces, a rotatable polishing wheel, a work support, means for pivoting said work support intermediate its ends, a rotatable drum on said work support on one side of the pivot means to engage the work for backing up the latter and to control the feed thereof, counter-balancing means on the work support on the other side of said pivot means to neutralize gravitational effect on said drum, means for driving said drum, a diaphragm, a boss attached to said work support, resting on said diaphragm and out of frictional sliding contact with other parts, and controlled pressure means for moving said diaphragm to urge the work through the work-engaging means of said work support toward said polishing wheel.

34. In a machine for polishing metal surfaces, a rotatable polishing wheel, a work support, means for pivoting said work support intermediate its ends, a rotatable member, skids on either side thereof on said work support at one side of the work support pivot, adjustable counter-balancing means on the work support on the other side of said work support pivot to neutralize gravitational effect of the work support and parts carried thereby, a diaphragm, a boss attached to said work support resting on said diaphragm and out of frictional sliding contact with other parts, and controlled pressure means for moving said diaphragm to urge the work through the work support towards said polishing wheel.

35. In a machine for polishing metal surfaces, a rotatable polishing wheel, a work support, means for pivoting said work support intermediate its ends, means on said work support on one side of the pivot means and below the polishing wheel to engage the work for backing up the latter and to control the feed thereof, coun-

ter-balancing means on the work support on the other side of said pivot means to neutralize gravitational effect on the work-engaging means, a diaphragm, a boss attached to said work support resting on said diaphragm and out of frictional sliding contact with other parts, controlled pressure means for moving said diaphragm to urge the work through the work-engaging means toward said polishing wheel, and means to limit 10 the movement of the work-engaging means to prevent its contacting the polishing wheel.

36. In a machine for polishing metal surfaces, a rotatable polishing wheel, a work support, means for pivoting said work support intermediate its ends, means on said work support on one side of the pivot means to engage the work for backing up the latter and to control the feed thereof, counter-balancing means on the work support on the other side of said pivot 20 means to neutralise gravitational effect on the work-engaging means, a diaphragm, a boss attached to said work support resting on said diaphragm and out of frictional sliding contact with other parts, controlled pressure means for moving said diaphragm to urge the work through the work-engaging means of said work support toward said polishing wheel, and separate means at the counter-balancing end of the work support to rock the latter away from the work.

37. In a machine for polishing metal surfaces, a rotatable polishing wheel, a work support, means for pivoting said work support intermediate its ends, means on said work support on one side of the pivot means to engage the work 25 for backing up the latter and to control the feed thereof, counter-balancing means on the carriage on the other side of said pivot means to neutralize gravitational effect on the work-engaging means, a diaphragm, a boss attached 30 to said carriage resting on said diaphragm and out of frictional sliding contact with other parts, and an air pressure chamber for operating said diaphragm, and means to adjust the counter-balancing means.

38. In a machine for polishing metal surfaces, a rotatable polishing wheel, a work support, means for pivoting said work support intermediate its ends, means on said work support on one side of the pivot means to engage the work 35 for backing up the latter and to control the feed thereof, counter-balancing means on the work support on the other side of said pivot means to neutralise gravitational effect on the work-engaging means, a diaphragm, a boss attached to said work support resting on said diaphragm and out of frictional sliding contact with other parts, and an air pressure chamber for 40 operating said diaphragm, and means to move the work-engaging means on said work support 45 away from the polishing wheel.

39. In a machine for polishing metal surfaces, a rotatable polishing wheel, a work support, means for pivoting said work support intermediate its ends, means on said work support on 50 one side of the pivot means to engage the work for backing up the latter and to control the feed thereof, counter-balancing means on the work support on the other side of said pivot means to neutralise gravitational effect on the 55 work-engaging means, a diaphragm engaging a portion attached to said work support and an air pressure chamber for operating said di-

aphragm, and means to move the work-engaging means in said work support away from the polishing wheel and at the same time automatically relieve the diaphragm pressure thereon.

40. In a machine for polishing rectilinear metal 5 surfaces, a rotatable polishing wheel having a peripheral work engaging surface of a definite character which is maintained during the polishing operation, a rockable work support arranged beneath said wheel, means for counter-balancing 10 said work support and movable to a plurality of adjusted positions relative to said support, a controlled fluid pressure device operable by fluid at predetermined pressure values for transmitting a predetermined pressure value corresponding 15 to the intensity of the applied fluid, and means responsive with said pressure device and actuated thereby to rock said work support toward the polishing wheel and lift the work upwardly into engagement therewith.

41. In a machine for polishing metal surfaces, a rotatable polishing wheel, a work support, means for pivoting said work support intermediate its ends, means on said work support on one side of the pivot means to engage the work 25 for backing up the latter, a diaphragm, and controlled fluid pressure means for moving said diaphragm to urge the work through the work engaging means of said work support toward said polishing wheel.

42. In a machine for polishing metal surfaces, a rotatable polishing wheel, a work support, means for pivoting said work support intermediate its ends, means on said work support on one side of the pivot means to engage the work 35 for backing up the latter, a diaphragm, a boss attached to said work support resting on said diaphragm and out of frictional contact with the other parts, and a fluid pressure chamber for operating said diaphragm to urge the work 40 through the work engaging means of said work support toward said polishing wheel.

43. In a machine for polishing metal surfaces, a rotatable polishing wheel, a work support, means for pivoting said work support intermediate its ends, a rotatable member on said work support on one side of the pivot means to engage the work for backing up the latter, a diaphragm, a boss attached to said work support resting on said diaphragm and out of frictional sliding contact with the other parts, and a controlled fluid 45 pressure means for operating said diaphragm to urge the work through the work engaging means of said work support toward said polishing wheel.

44. In a machine for polishing metal surfaces, a rotatable polishing wheel, a work support, means for pivoting said work support intermediate its ends, means on said work support on one side of the pivot means to engage the work for 50 backing up the latter, a diaphragm, a boss attached to said work support resting on said diaphragm and out of frictional sliding contact with the other parts, a fluid pressure chamber for operating said diaphragm to urge the work through the work engaging means of said work support toward said polishing wheel, and means to move the work engaging means on said work support away from the polishing wheel and at the same time automatically relieve the diaphragm 55 pressure thereon.

DAVID E. MULHOLLAND.
